United States Patent Office

Des. 185,457
Patented June 9, 1959

185,457

WINE CART OR SIMILAR ARTICLE

Victor D. Molitor, Englewood, Colo.

Application February 17, 1958, Serial No. 49,683

Term of patent 14 years

(Cl. D14—3)

FIG. 1

FIG. 2

Fig. 1 is a front perspective view of a wine cart embodying my new design; and

Fig. 2 is a rear perspective view of the wine cart of Fig. 1.

The essential features of my design are shown in full lines.

I claim:

The ornamental design for a wine cart or similar article, as shown and described.
